UNITED STATES PATENT OFFICE.

KONRAD P. SWANSTROM, OF SEATTLE, WASHINGTON.

SELECTING CAM FOR KNITTING MACHINES.

Application filed April 3, 1922. Serial No. 549,350.

To all whom it may concern:

Be it known that I, KONRAD P. SWANSTROM, a citizen of the United States, residing at Seattle, county of King and State of Washington, have invented new and useful Improvements in Selecting Cams for Knitting Machines; and I do hereby declare that the following is a full, clear, and exact specification, such as will enable others skilled in the art to which they appertain to make and use the same.

The invention is a device which may be attached to knitting machines which will make it possible to raise every alternate pair of needles or one or any number of needles and skip any number of needles so that several different colors of yarn may be knitted into one piece of goods in any desired design.

The object of the invention is to provide a small cam which may replace the needle raising lever on a circular knitting machine so that alternate pairs of needles may be raised instead of all of them.

Another object of the invention is to provide a small cam which may be pivotally mounted in the track of a flat knitting machine so that two or any number of needles may be raised at given intervals.

And a further object of the invention is to provide a small cam which may be attached to the guides of a circular knitting machine which will make it possible to raise some of the needles at regular intervals in order to knit different colored yarn into one piece of material with each of the different colors forming ribs, without the use of additional attachments as is now required.

With these ends in view the invention embodies a flat piece of circular material with a hole thru it having a prong on one side and a small projection at a point on the other side which would be at an angle of about 90 degrees from the centerline of the prong.

Other features and advantages of the invention will appear from the following description taken in connection with the drawings, wherein:

Figure 1 is a side elevation of a unit of a circular knitting machine with parts broken away.

Figure 2 is a large detail of the cam in the act of raising two of the needles.

Figure 3 is a similar detail showing the cam raised to miss the third needle.

Figure 4 is a similar detail showing the cam in the act of discharging the needles.

Figure 5 is a similar detail showing the cam returned to its normal position.

Figure 6 is an alternate arrangement showing the cam attached to a flat machine.

In the drawings I have shown my device as it would be installed on a circular knitting machine in Figure 1 wherein numeral 1 indicates the hub of the device which has a hole 2 in its center, a prong 3 on one side, and a projection 4 at about right angles to the prong. This device may be attached to a standard post such as I have shown in Figure 1 with the top in dotted lines and indicated by the numeral 5, by placing it on the end of a small rod which may project thru a hole in the post and which may have a spring on its outer end to return the device to the position shown. In the present construction a lever 6 is placed upon the end of this small rod and the spring holds it down constantly so that it will raise all of the needles and in its normal position it would be in about the same position as the prong 3 of my device. In Figure 1 I have shown another the post 5a set ahead and reversed the lever 6 so that it will hold the needles down as they approach my device, and it will be seen that as the cam shaped ring 7 moves to the right the butts of two of the needles will be raised and then the prong 3 will raise over the next two butts so that they may pass under them.

The construction of my device is practically the same as that of the lever 6 with the exception of the projection 4 at the upper end of the lever. I have endeavored to explain the action of this projection in the Figures 2, 3, 4 and 5 and in describing it will refer to the butts of the needles passing by the device with consecutive numerals. In Figure 2 the device is in the same position as shown in Figure 1 wherein the butts 10 and 11 have been forced up the inclined surface of the device. As the ring 7 moves one notch the hub 10 bearing against the projection 4 will cause the device to rotate about a pin thru the hole 2 so that the prong 3 will raise to the position shown in Figure 3. In the position shown in Figure 3 the ring has not moved a complete notch and as it completes its movement the butt 10 will slip off of the projection 4 and the spring on the rod which holds the device will cause the prong 3 to drop to the position shown

in Figure 4. In the next movement the butt 11 will act against the projection 4 and cause the prong 3 to raise which will permit the butt 13 to pass under it as did the butt 12 in the previous movement. Then as there are no other butts on the incline to operate the device it will remain in the position shown in Figure 5 until the butt 14 has moved up to the position formally occupied by the butt 10 as shown in Figure 2. At this time the butt 15 will be on the incline in the position occupied by the butt 11 in Figure 2, and then as each of these butts 14 and 15 operate the device by acting against the projection 4 the prong 3 will raise to allow two more butts to pass under it as did the butts 12 and 13 when the butts 10 and 11 were acting against the projection 4. As this operation is continued it will be seen that every alternate pair of butts will be raised while the balance will drop down and pass under the device and as one color of yarn is fed to the needles the two needles whose butts have been raised will come up and take the yarn; and by placing any number of these devices around the circle with a different color of yarn for each one it will be possible to knit a piece of material with different colored ribs in it. It will be seen that as this device may be installed in any machine and in the same place as that now occupied by the lever 6 and may be placed on the same rod so that it will be operated by the same spring the process of installing it will be very simple.

I have shown an alternate arrangement in Figure 6 which shows how the device may be used on flat machines and altho I have only shown one type it is understood that the same principle may be used for all machines, by slightly changing its construction to meet the requirements of the different designs. In this design I have shown a slot

16 cut in the end of the guide 17 and a hole 18 drilled thru it. A lever 19 having a projection 20 on it may be pivotally mounted in the slot on a pin 21 in the holes 18 and it will be seen that as two of the butts pass upon the lever they will act upon the projection 20 and cause the lever to raise to the position shown in dotted lines so that it will allow the next two butts to pass by, which action will be exactly similar to that of the device for circular machines hereinbefore described.

It will be seen that changes may be made in the construction without departing from the spirit of the invention, as the design of the device may be slightly changed or its location in the ring may be altered in order to produce different designs and a different means may be used for supporting it. It will also be seen that its construction will have to be considerably changed to fit different styles of flat machines and it may also be changed so that it will raise one needle instead of two at which time it may permit any number of needles to pass under it or it may be altered so that it will raise any number of needles and let any number of needles pass under it.

Having thus fully described the invention what I claim is new and desire to secure by Letters Patent is:—

A device of the type described embodying 75 a flat circular piece of material; a prong extending from one side of the material; a small projection at the top of the piece of material; a smooth curved surface from the end of the prong to the projection; and a 80 hole thru the piece of material by which it may be pivotally supported on a knitting machine so that it will engage butts on the needles in order to raise alternate pairs of the needles.

KONRAD P. SWANSTROM.
